HERBERT B. TAYLOR, OF ROCHESTER, NEW YORK, ASSIGNOR TO GENERAL RAILWAY SIGNAL COMPANY, OF GATES, NEW YORK, A CORPORATION OF NEW YORK.

MECHANICAL TIME-RELEASE FOR INTERLOCKING DEVICES.

1,245,133.

Specification of Letters Patent. Patented Oct. 30, 1917.

Application filed July 1, 1915. Serial No. 37,516.

To all whom it may concern:

Be it known that I, HERBERT B. TAYLOR, a citizen of the United States, and a resident of the city of Rochester, in the county of 5 Monroe and State of New York, have invented a new and useful Mechanical Time-Release for Interlocking Devices, of which the following is a specification.

This invention relates more particularly 10 to a mechanical time release of the general class applied to signal operating levers or parts to assure lapse of a predetermined time between adjustment of a semaphore or other signal lever to the normal indication 15 position and the release of connected levers or parts operating switches, derails, detector bars, or other movable members of interlocking mechanisms used more especially in railway service.

20 The invention has for its main objects to provide a time release mechanism whose arresting bolt or part is positively and fully forced into position to prevent return of the operated interlocking lever or device to full 25 normal position during the predetermined time interval necessarily elapsing before operating the switch, derail or other movable member; and also to provide a time release mechanism having parts mutually adjustable 30 to widely and accurately vary the duration of said time interval whereby the same standard time release mechanism may be used in practically all situations to which a device of this character is adapted; and also 35 to provide a time release mechanism whose arresting bolt or part when once projected to prevent return of the interlocking lever or device to full normal position remains fully projected until after expiration of the time 40 interval for which the release is set, and is then instantly and fully withdrawn or snapped from the path of movement of the interlocking lever or device; and further to provide a simple and efficient time release 45 mechanism the adjustment of which for lever arresting function automatically stores up or generates within itself the power necessary for later actuating its parts which control withdrawal of the lever arresting bolt at the predetermined time for which 50 the release is adjusted.

Specifically the device hereinafter described and claimed when applied to one of the levers of the well known railway inter-

locking machine, such, for instance, as a 55 signal lever, provides a means whereby the operator or manipulator of such levers is prevented from returning the lever to which the means is applied from reverse position to the full normal position until after the 60 lapse of a predetermined time measured from the time the lever is placed in the normal indication position. It is well known to those skilled in the railway signaling art, and especially that portion of the art relating 65 to electric interlocking machines for railway signaling, that the return of a lever from the reverse position almost to the normal position causes the function operated by that lever to be returned to the normal position, but levers controlling other functions conflicting with the functions controlled by the first mentioned lever are not fully released by reason of the mechanical interlocking 70 on the machine until the return of 75 the lever to full normal position so that, for instance, if a lever is returned almost to the normal position thereby causing the function controlled by that lever to be returned to the normal position, and if a certain 80 definite interval of time is caused to lapse after such movement of the lever before the lever can be returned to the full normal position, then any switches or signals, the levers of which are controlled 85 through the mechanical interlocking by the first mentioned lever, are still so locked that they cannot be moved from the normal position so as to operate the functions controlled by them. Therefore, although a leverman 90 may return the signal to the normal position when the means hereinafter described is applied to the lever controlling that signal, he cannot until after the lapse of a definite interval of time measured from or 95 after movement of the lever to normal indication position, return the switches over which that signal controls movements to their normal positions, and so cannot set up another route for a different movement of 100 trains. This inability of the signal man to quickly change from one route to another prevents him from allowing train movements so rapidly one after the other that there is liability of a collision.

Other objects and advantages will appear as the description of the invention progresses, and the novel features of the inven-

tion will be particularly pointed out in the appended claims.

Reference is made to the accompanying drawings forming part of this specification and in which Figure 1 is a partly broken out perspective view of the improved time release mechanism with the cover removed and the interlocking lever omitted; Fig. 2 is a detail side view of an end portion of the time release mechanism and part of the adjacent interlocking lever which is shown in full normal position relatively to the release mechanism; Fig. 3 is a detail side view of parts shown in Fig. 2, excepting the lever, and illustrates the position of parts after the preliminary or idle movements of the plunger; Fig. 4 is a partly sectional side view of the time release mechanism with the cover applied thereto and in vertical section and with the parts in positions corresponding to the reverse indication position of the lever, and Fig. 5 is a partly broken out plan view of the time release mechanism with the cover in horizontal section and its fastening removed, and with the parts in the normal relative positions shown in Figs. 1 and 2; Fig. 6 is a fragmentary end view of the righthand end portion of the mechanism shown in Fig. 1, said Fig. 6 being a section taken substantially on the line 6—6 in Fig. 2 and looking in the direction indicated by the arrows; and Figs. 7 and 8 are detail sections of the clutch forming part of the mechanism.

The numeral 1, indicates the time release mechanism base which has bolt holes 2, permitting its attachment to a lever guide or support in an interlocking machine. The base has other holes 3, permitting attachment to one end of it of any auxiliary device such as a lamp holding casing. To the base 1, are secured the opposite side plates 4, 4, of the frame of a motor shown as a clockworks mechanism which includes a main shaft 5, to which is fixed the inner end of a coiled spring 6, arranged between one frame plate 4, and a disk 7, fixed to the shaft 5. This spring is fixed at its outer end 8, to one of the transverse rods 9, which space apart the frame plates 4, 4. The shaft 5, fixedly carries an inner clutch member 10, which has a suitable number of peripheral recesses 11, in each of which is a clutch roller 12, which is normally urged around by a spring 13, to cause prompt clutching of the roller between the inclined end of the recess 11, and the inner face of an outer clutch casing member 14, which is fixed to the main driving gear 15, of a suitable gear train 16, supported in the frame 4, 4, and including an escapement 17, having the ordinary speed controlling function. As the shaft 5, is turned clockwise in direction of arrow α , the clutch rollers 12, automatically release the outer clutch member 14, and si-

multaneously the spring 6, is coiled more tightly to increase its torsion, and thus store power in the clockworks while the gear train 16, is at rest. When the shaft 5, rotates counter-clockwise, the clutch rollers 12, will instantly and without appreciable lost motion, engage the outer clutch member 14, and thus operate the gear train by the now un-coiling spring 6. This spring is coiled more tightly by the turning of a gear wheel 18, which is fixed to the shaft 5, and is itself turned by the engaging teeth 19, of a sector 20, which has a bearing upon a shaft 21, fitted in lugs 22, 22, rising from one end of the base 1. The shaft 21, may be fixedly held by a cotter pin 23, passed through one lug 22.

The sector 20, has a tail portion in which is fitted a vertically adjustable screw 24, by which the desired timing of the lever release is accurately adjusted as hereinafter more fully explained. Any means may be used for securely locking the screw 24, after it is adjusted in the sector 20, the means shown being a set screw 25, engaging divided portions of the sector tail made by vertically sawing or slitting it at 26. Upon the sector supporting shaft 21, is also loosely mounted a rocking lever 27, preferably comprising two spaced arms connected by a crossbar. The bearing of the sector 20, lies between inner parts of the fork limbs of the lever 27, which also receive between them the forked upper end of a vertically movable locking bolt 28, between whose fork limbs 29, 29, the inner part of the sector 20, freely passes. The lower part of the bolt 28, has a sliding fit in the base 1, and the upper fork limbs 29, of the bolt are preferably guided by pins 30, fixed in the frame lugs 22, and having reduced inner portions entering slots 31, of the bolt limbs. Each bolt limb 29, has an upper shoulder 32, and both shoulders are adapted for simultaneous engagement by the lower fork ends of a latch 33, which is pivoted to the upper ends of the base lugs 22, and is normally held to the bolt limbs 29 by a spring 34. A shoulder 35, of the sector 20, may enter between the fork limbs of the latch 33, and press against a transverse pin 36, fixed to said limbs for at proper time tripping the latch 33, from the shoulders 32, of the bolt 28, to allow it to be instantly lifted out of the path of a shoulder 44 on a subjacent interlocking bar or lever 37, by the inner ends of lifting springs 38, acting underneath pins 39, fixed to and projecting laterally from opposite sides of the bolt. These pins 39, underlie inner ends of the fork limbs of rocking lever 27, to and between the outer ends of which is pivoted by a pin 40, the upper end of a vertically movable plunger 41, which has a guiding bearing in the base 1. The plunger 41, is forcibly raised by riding up the in-

cline 42 of a notch of the lever 37, when said lever is moved to the left hand in direction of the arrow *b*, and the plunger then rests upon the upper edge 43, of the lever, and at this time the locking bolt 28 will have been positively forced down or projected in front of the locking shoulder 44, of lever 37, by downward pressure of the inner ends of the rocking lever 27, upon the bolt pins 39, and 10 against the tension of the springs 38. Any suitable sheet metal or other casing 45, is slipped over the time release mechanism as shown in Figs. 4 and 5 of the drawings, and a thumb nut 46, screwing upon a stud 47, 15 fixed to one of the frame plate spacing rods 9, holds the casing in position to exclude dust and dirt from the mechanism. A hammer 48 is pivoted on one frame tie-rod 9, to be struck by the quickly rising bolt 28, 20 and forced against the resonant casing 45, for giving a distinct click sound notifying the towerman that the bolt 28, has been withdrawn to permit full operation by the interlocking lever 37, of the usual interlocking tappet 49, carrying an anti-friction roller 25 50 entering the lever slot 51.

In view of the above description a comparatively brief further explanation of the operation of the time release mechanism will suffice, as follows: When the interlocking lever or bar 37, is in the normal position shown in Fig. 2 of the drawings, and the plunger 41, and bolt 28, and directly coacting parts are in the normal relative positions shown in Figs. 1 and 2, the gear 18 engages the lowermost teeth 19, of the sector 20. If now the lever 37 be moved from normal position, and in direction of the arrow *b*, to a reverse indication position shown in 30 Fig. 4, the first effect is to move the lever shoulder 44, beyond the bolt 28, about as the chamfered lower end of the plunger 41 is struck by the lever incline 42, and said incline then forces the plunger upward and 35 simultaneously through the rocking lever 27, positively forces the bolt 28 downward. A comparison of Figs. 2 and 3, will show that the upward movement of plunger 41, cannot turn the sector 20, until after the 40 plunger strikes the sector screw 24, whereupon a further upward plunger movement turns the sector counter-clockwise to the position shown in Fig. 4, and thereby positively turns gear wheel 18, and shaft 5, 45 clockwise in direction of the arrow *a*, thus more closely coiling the clockworks spring 6, and storing its increased power while the clutch rollers 12 release clutch member 14, and the gear train 16 is inoperative. As 50 the plunger 41 rode fully up the lever incline 42, and upon the lever edge 43, the bolt 28, was projected in front of the lever shoulder 44, and the latch 33 then was forced by its spring 34 above the bolt shoulders 32, 55 thus locking the bolt projected downward as shown in Fig. 4, thereby preventing return of the lever 37, to full normal position until after lapse of the time interval for which the time release mechanism is set and the consequent snap-withdrawal of the bolt 28, above the lever shoulder 44. When the lever 37 and tappet 49, have relative interlocking positions shown in Fig. 4, they prevent movement from normal position of other slides or levers controlling other 60 switches and signals conflicting with the signal controlled by lever 37, and switches controlled by levers interlocked with lever 37, and as shown and described in United States Patent No. 752,127, granted to John D. Taylor, on February 16th, 1904. After expiration of the definite time interval for which the release device is adjusted, and the consequent automatic withdrawal of bolt 28, the lever 37 may be forced to full normal position thereby releasing through the mechanism of the interlocking machine all levers dependent upon lever 37, so that other routes which would conflict with those controlled by lever 37, may be set up to permit further train movements. The operation in detail of the parts for causing the withdrawal of the bolt 28 after the expiration of the time interval for which the mechanism is set is as follows: when the lever 37 is moved toward the normal position, that is, toward the right as viewed in Fig. 4, its movement is arrested at the normal indication position by the engagement of the bolt 28 with the shoulder 44 in the upper edge of said lever; and since the plunger 41 is released by this movement of the lever at the same time, the spring 6 commences to unwind. During the first part of the unwinding movement of the spring 6, which 65 turns the shaft 5 and the inner clutch member 10 in a counterclockwise direction, said inner clutch member 10 is clutched to the outer clutch casing 14 and immediately commences to drive the gear 15 gradually at the speed determined by the clockwork mechanism. Fig. 4 of the drawings shows that turning of the sector 20, by contact of the rising plunger 41, with the sector screw 24, 70 had moved the sector shoulder 35 some distance back from the latch pin 36, and therefore the sector must reversely turn a slightly greater distance as the gear 18 turns counter-clockwise under influence of the uncoiling spring 6, before the sector shoulder 35 75 can strike the latch pin 36, and force the latch 33 from the bolt shoulders 32. When this happens the springs 38 instantly snap the bolt 28 upward clear above the shoulder 44 of lever 37, thus permitting movement of the lever to full normal position. About as the return movement of the sector 20 to the 80 normal position shown in Figs. 1, 2 and 3, is completed, a shoulder 52, on the sector, strikes the tripped latch 33 to limit move- 85

ment of the sector and thus stop the nearly run down clockworks 16. It is obvious that the time interval elapsing before the locked or arrested lever 37, may be returned to full normal position depends upon the extent of backward movement of the sector shoulder 35, from the latch pin 36, after contact of the rising plunger 41, with the sector screw 24, hence by turning this screw farther downward or forward in the sector tail than is shown in the drawings the plunger 41 will earlier strike the screw 24, and consequently will turn the sector 20 counterclockwise farther than herein shown, and move its shoulder 35 relatively farther away from the latch pin 36, as the plunger is forced fully upward by the incline 42, of lever 37. This would result in turning the gear 18, by the sector 20, farther around in direction of arrow 20 *a*, and would thereby relatively prolong reverse operation of the clockworks 16, and the dependent return movement of the sector before its shoulder 35 could strike the latch pin 36, and trip the latch from the shoulders 32, of the projected bolt 28, to permit snapping upward of the bolt by the springs 38, for releasing the interlocking lever 37. Contrariwise, if the sector screw 24 be turned farther upward or backward in the sector tail, the plunger 41, will later strike the screw 24, and impart relatively less counterclockwise movement to the sector and clockwise movement to the gear 18, as the plunger is moved fully upward by the lever 37, thereby moving the sector shoulder 35 a less distance from the latch pin 36, than is shown in Fig. 4, and thus requiring a shorter reverse operation of the clockworks to carry the sector shoulder 35 to the latch pin 36, and trip the latch from the bolt shoulder 32, to allow the springs 38, to snap the bolt 28, upward for permitting return of the lever 37, to full normal position. Obviously, any means other than the screw 24, may be used for assuring variable turning of the sector 20, through a longer or shorter arc as the plunger 41 is fully raised by the interlocking lever 37; and any means may be used to couple the plunger 41, to the lever arresting bolt 28, for forcing the bolt downward as the plunger is forced upward by the interlocking lever 37; and the spring-actuated clockworks may be substituted by any equivalent motor; and the interlocking part actuating the plunger may have rotary instead of reciprocating movement.

Although I have particularly described the construction of one physical embodiment of my invention, and explained the operation and principle thereof; nevertheless, I desire to have it understood that the form selected is merely illustrative, but does not exhaust the possible physical embodiments of the idea of means underlying my invention.

What I claim as new and desire to secure by Letters Patent of the United States, is:

1. A time release mechanism comprising a bolt, a plunger, means simultaneously moving them in reverse directions, an interlocking device, a latch holding the bolt projected thereby arresting the interlocking device, means automatically withdrawing the bolt when the latch is tripped therefrom, a motor, and a sector engaged by the motor and automatically turned in one direction by bolt-projecting movement of the plunger and having a part automatically tripping the latch from the projected bolt as the sector is reversely turned by the motor. 75

2. A time release mechanism comprising a bolt, a plunger, means simultaneously moving them in reverse directions, an interlocking device, a latch holding the bolt projected thereby arresting the interlocking device, means automatically withdrawing the bolt after the latch is tripped therefrom, clockworks mechanism, and a sector engaged by the clockworks and automatically turned in one direction by bolt-projecting movement of the plunger thereby storing power in the clockworks, said sector having a part automatically tripping the latch from the projected bolt as the sector is reversely turned by the clockworks. 80 85

3. A time release mechanism comprising a bolt, a plunger, means simultaneously moving them in reverse directions, an interlocking device comprising a reciprocatory lever or bar having a recess provided with an incline actuating the plunger for positively projecting the bolt and also having a shoulder preventing full return of the lever to normal position after the bolt is projected, a latch holding the bolt projected, means automatically withdrawing the bolt after the latch is tripped therefrom, a motor, and a sector engaged by the motor and automatically turned in one direction by bolt-projecting movement of the plunger, said sector having a part automatically tripping the latch from the projected bolt as the sector is reversely turned by the motor. 100 105 110

4. A time release mechanism comprising a bolt, a plunger, a rocking lever moving them simultaneously in reverse directions, an interlocking device operating the plunger thereby positively projecting the bolt, a latch holding the bolt projected thereby arresting the interlocking device, means automatically withdrawing the bolt after the latch is tripped therefrom, clockworks mechanism, and a sector engaged by the clockworks and automatically turned in one direction by bolt-projecting movement of the plunger thereby storing power in the clockworks, said sector having a part automatically tripping the latch from the projected bolt as the sector is reversely turned by the clockworks. 115 120 125 130

5. A time release mechanism comprising a bolt, a plunger, means simultaneously moving them in reverse directions, an interlocking device operating the plunger thereby positively projecting the bolt, a latch holding the bolt projected thereby arresting the interlocking device, means snapping the bolt to withdrawn position after the latch is tripped, a motor, and a sector engaged by the motor and automatically turned in one direction by bolt-projecting movement of the plunger, said sector having a part automatically tripping the latch from the projected bolt as the sector is reversely turned by the motor.

10 6. A time release mechanism comprising a bolt, a plunger, means simultaneously moving them in reverse directions, an interlocking device operating the plunger thereby positively projecting the bolt, a latch holding the bolt projected thereby arresting the interlocking device, means automatically withdrawing the bolt after the latch is tripped therefrom, clockworks mechanism including a wheel, a coiled spring and a clutch device, and a sector engaging said wheel and automatically turned in one direction by bolt projecting movement of the plunger as the clutch releases and while the main gearing of the clockworks is at rest and while the spring is more closely coiled to store power in the clockworks, said sector having a part automatically tripping the latch from the projected bolt as the sector is reversely turned by the clockworks driven by the uncoiling spring.

15 7. A time release mechanism comprising a bolt, a plunger, means simultaneously moving them in reverse directions, an interlocking device, a latch holding the bolt projected thereby arresting the interlocking device, means automatically withdrawing the bolt after the latch is tripped therefrom, a motor, a sector engaged by the motor and automatically turned in one direction by bolt-projecting movement of the plunger and having a part automatically tripping the latch from the projected bolt as the sector is reversely turned by the motor, and adjustable means adapted to vary the normal distance between parts of the plunger and sector whereby the time interval between bolt-projecting movement of the plunger and tripping of the latch from the bolt by the sector may be lengthened or shortened to correspondingly vary the time of withdrawal of the bolt.

20 8. A time release mechanism comprising a bolt, a plunger, means simultaneously moving them in reverse directions, an interlocking device, a latch holding the bolt projected thereby arresting the interlocking device, means automatically withdrawing the bolt after the latch is tripped therefrom, clockworks mechanism and a sector engag-

25 ing a wheel of the clockworks and automatically turned in one direction by bolt-projecting movement of the plunger thereby storing power in the clockworks, said sector having a part automatically tripping the latch from the projected bolt as the sector is reversely turned by the clockworks, and adjustable means adapted to vary the normal distance between parts of the plunger and sector whereby the time interval between the bolt-projecting movement of the plunger and the tripping of the latch from the bolt by the sector may be lengthened or shortened to correspondingly vary the time of withdrawal of the bolt.

30 9. A time release mechanism comprising a bolt, a plunger, means simultaneously moving them in reverse directions, an interlocking device, a latch holding the bolt projected thereby arresting the interlocking device, means automatically withdrawing the bolt after the latch is tripped therefrom, a motor, a sector engaged by the motor and automatically turned in one direction by bolt-projecting movement of the plunger and having a part automatically tripping the latch from the projected bolt as the sector is reversely turned by the motor, and a screw adapted to vary the normal distance between parts of the plunger and sector whereby the time interval between the bolt-projecting movement of the plunger and the tripping of the latch by the sector may be lengthened or shortened by adjusting the screw to correspondingly vary the time of withdrawal of the bolt.

35 10. A time release mechanism comprising a bolt having lateral shoulders, a plunger, a rocking lever pivoted at its outer end to the plunger and having a forked inner end, a motor, a sector journaled on the rocking lever shaft and within the fork of said lever, said bolt also having a forked upper end embraced by the rocking lever fork and receiving within it the inner part of the sector which engages the motor, the lever being adapted to project the bolt by pressure upon its lateral shoulders, and a latch holding the bolt projected thereby arresting the interlocking device, said sector being turned counter-clockwise by bolt-projecting movement of the plunger and having a part automatically tripping the latch from the projected bolt as the sector is reversely turned by the motor and means automatically withdrawing the bolt after the latch is tripped from it by the sector.

40 11. A time release mechanism comprising a bolt having lateral shoulders, a plunger, a rocking lever pivoted at its outer end to the plunger and having a forked inner end, a motor, a sector journaled on the rocking lever shaft and within the fork of said lever, said bolt also having a forked upper end embraced by the rocking lever

fork and receiving within it the inner part of the sector which engages the motor, the lever being adapted to project the bolt by pressure upon its lateral shoulders, and a latch holding the bolt projected thereby arresting the interlocking device, said sector being turned counterclockwise by bolt-projecting movement of the plunger and having a part automatically tripping the latch from the projected bolt as the sector is reversely turned by the motor, and a spring automatically snapping the bolt to withdrawn position after the latch is tripped from it by the sector.

15 12. A time release mechanism comprising a base, a bolt having a sliding bearing in the base, a rocking lever fulcrumed on a shaft held to opposite side lugs of the base and pivoted to the outer end of the plunger and having a forked inner end, a motor, a sector journaled on the rocking lever shaft and within the fork of said lever, said bolt also having a forked upper end embraced by the rocking lever fork and receiving within it the inner part of the sector which engages the motor, and a latch holding the bolt projected thereby arresting the interlocking device, said sector being turned counterclockwise by bolt-projecting movement of the plunger and having a part automatically tripping the latch from the projected bolt as the sector is reversely turned by the motor, said bolt having pins or shoulders projecting laterally under the fork ends of the rocking lever, and springs acting under the bolt pins or shoulders and normally withdrawing the unlatched bolt.

20 13. A time release mechanism comprising a base, a bolt having a sliding bearing in the base, a rocking lever fulcrumed on a shaft held to opposite side lugs of the base and pivoted to the outer end of the plunger and having a forked inner end, a motor, a sector journaled on the rocking lever shaft and within the fork of said lever, said bolt also having a forked upper end embraced by the rocking lever fork and receiving within it the inner part of the sector which engages the motor, and a latch holding the bolt projected thereby arresting the interlocking device, said sector being turned counterclockwise by bolt-projecting movement of the plunger and having a part automatically tripping the latch from the projected bolt as the sector is reversely turned by the motor, said bolt having pins or shoulders projecting laterally under the fork ends of the rocking lever, and springs acting under the bolt pins or shoulders and normally withdrawing the unlatched bolt.

25 14. In an interlocking system for railways, in combination: a lever having a normal position, a reverse position and a normal indication position; means operated mechanically by the movement of said lever to its reverse position for preventing the return movement of said lever to its full normal position; and means for automatically rendering said first mentioned means ineffective after the lapse of a predetermined time following the movement of said lever to its normal indication position.

30 15. In an interlocking system for railways, in combination: a lever having a normal position, a reverse position and a normal indication position and having a shoulder formed thereon; a bolt arranged to cooperate with said shoulder and prevent a return movement of said lever to its full normal position; means operated automatically by said lever during its movement to its reverse position for moving said bolt into position to engage said shoulder; and means for automatically withdrawing said bolt from its locking position after the lapse of a predetermined time following the movement of said lever to its normal indication position.

35 16. In an interlocking system, in combination: a lever having a normal position, a reverse position and a normal indication position; a bolt adapted to prevent the return movement of said lever to its full normal position; means operated automatically by said lever during its movement to its reverse position for moving said bolt to its locking position; means tending to move said bolt from its locking position to its unlocking position; a catch for automatically holding said bolt in its locking position after it has been moved to that position; and means acting after the lapse of a predetermined time following the movement of said lever to its normal indication position for automatically tripping said catch to permit the quick unlocking movement of said bolt.

HERBERT B. TAYLOR.
